United States Patent Office.

DANIEL CURRIE, OF ST. CHARLES, MISSOURI.

Letters Patent No. 83,766, dated November 3, 1868.

IMPROVEMENT IN ROTARY STEAM-ENGINES.

The Schedule referred to in these Letters Patent and making part of the same.

To all whom it may concern:

Be it known that I, DANIEL CURRIE, of St. Charles, in the county of St. Charles, and State of Missouri, have made certain new and useful Improvements in Rotary Steam-Engines; and I do hereby declare that the following is a full and clear description thereof, reference being had to the accompanying drawings, and to the letters of reference marked thereon.

The object of this invention is to produce a rotary engine with continuous action, by the employment of two cylinders, thereby entirely avoiding any dead-point.

The combination of two cylinders, either rotary or reciprocating, is not a new feature in steam-engines for producing this result, neither are the cylinders of the present invention essentially new in and of themselves; but the combination of the cylinders herein-after described presents a new and novel feature, and in operation produces a much better result than any heretofore produced.

This invention furthermore relates to certain new and useful details of construction, as will be hereinafter more fully explained.

To enable those skilled in the art to make and use my improved engine, I will proceed to describe its construction and operation.

Figure 1, of the drawings, is a transverse sectional elevation of the improved engine.

Figure 2 is a longitudinal sectional elevation of one cylinder.

Figure 3 is a sectional elevation of one cylinder, showing the method of packing the sides.

Figure 4 is a sectional elevation of one cylinder, exhibiting the steam and exhaust-ports, the method of packing the periphery of the piston, and the eccentricity of the same.

In this engine, two cylinders, A A', are employed, the external portions of which may be of any convenient size or form, and the internal portions of which will be bored out in cylindrical cavities, a, in which the pistons B B' will revolve.

The two rotary pistons B B' are secured to a common shaft, C, which passes through stuffing-boxes in the sides of the cylinders, in the usual manner.

Each of the cylinders is provided with a sliding head, D or D', which fit closely down to the pistons; and as these pistons are fixed to the shaft C eccentrically, and with their longer radii diametrically opposite, it is evident that one of the heads will be up when the other is down, as is clearly shown in fig. 1.

In order to make the motion and positions of these heads conform to the motion and positions of the pistons, each of them is attached to a sliding rod, d or d', and these rods are coupled, by means of the connecting-rods d² d³, with the working-beam D². In this manner the motions and positions of the pistons and sliding heads are made to harmonize throughout the entire length of each and every stroke or revolution.

A steam-chest, E, having a longitudinal partition, e, is placed on top of the two cylinders A A'. The partition e subdivides the steam-chest into two compartments, e¹ e², and these compartments are connected with the cylinder-chambers by means of the ports e³ e⁴,

the arrangement being such that each of the said compartments is connected, by means of its ports, with both of the cylinders.

No valves are used in connection with the ports e³ e⁴, but the steam is allowed to enter, or be excluded from either chamber, e¹ e², by simply changing the stop-cock connections with the steam or exhaust-pipes, (not shown.)

From this description, it is evident the steam may be admitted to either side of the cylinder at pleasure, and the engine may be reversed by simply changing pressure of steam from one of the chambers, e¹ e², to the other.

"Forward" and "backward," with this engine, are only relative terms, as the engine will work in one direction equally as well as in the other.

The direct pressure of steam being admitted to one or the other of the chambers e¹ e², the exhaust will be allowed to pass through the other.

By arranging the two pistons B B', on the shaft C, as hereinbefore described, it is evident that one or the other of them will all the time be exposed to the minimum pressure of the steam, and consequently the motion will be uniform.

The pistons B B' are perfectly cylindrical in form, with the exception of that portion included between the points x x', as is shown in fig. 4; and in that portion of them their periphery is curtailed so as to allow it to come in contact with the side of the cylinder the entire distance between the said points x x'.

The length of the line x x' is sufficient to allow the required amount of lap to prevent steam blowing through the engine. Thus, it will be seen, that if the piston be revolving in the direction of the arrow b, the line x x' will cover the port e³, until the port e⁴ is completely covered, and the steam is thereby cut off.

A packing, b¹, is inserted into the wide side of the piston, as is shown in fig. 4, and a spring, b², at the bottom of the packing, throws it out in such a manner as to keep it in contact with the side of the cylinder, and in this manner a perfect packing between the parts is maintained.

The sides of the pistons are packed by means of the cylindrical pieces G, which are fitted into the ends of the cylinders, and ground up to the pistons. The packings G are to be set up to the pistons by means of the set-screws g.

What I claim as my invention, and desire to secure by Letters Patent, is—

1. The arrangement of the steam-chest E with the chambers e¹ e² and the cylinders A A', as herein set forth.
2. The arrangement of the cylinders A A', piston-wheels B B', with their periphery curtailed on one side, as shown at x x', together with the sliding heads D D', rods d d', links d² d³, and beam D², all constructed as herein shown and described.

DANIEL CURRIE.
